UNITED STATES PATENT OFFICE.

HOMER CLYDE SNOOK, OF PHILADELPHIA, PENNSYLVANIA.

POLYPHASE X-RAY SYSTEM.

1,131,870.

Specification of Letters Patent. Patented Mar. 16, 1915.

Application filed December 28, 1908. Serial No. 469,355.

To all whom it may concern:

Be it known that I, HOMER CLYDE SNOOK, a citizen of the United States, residing at Philadelphia, county of Philadelphia, and 5 State of Pennsylvania, have invented certain new and useful Improvements in Polyphase X-Ray Systems, of which the following is a specification.

My invention relates to a system and apparatus for producing X-rays, and has particular reference to the production of very intense X-rays, and non-intermittently, with a maximum efficiency of conversion, from a polyphase current supply.

15 My invention resides in a system and apparatus for exciting an X-ray tube at very high density and with a substantially constant stream of energy passing through the X-ray tube to maintain a practically continuous excitation at high intensity.

20 My invention resides also in other features hereinafter described and claimed.

As stated above, by my invention having recourse to a polyphase current supply, an 25 X-ray tube may be excited at very high intensity with non-intermittent or substantially constant stream of energy passing through the X-ray tube to maintain a practically continuous excitation at high intensity. An important technical result flowing from such a system is at least two fold, first, notwithstanding the high intensity excitation of the X-ray tube, destruction of the target in the vicinity of the focus spot 30 by bombardment by cathode particles is prevented or is a minimum considering the great amount of energy liberated; secondly, notwithstanding the high excitation of the X-ray tube, the vacuum of the tube is prevented from becoming erratic, that is, either 35 rising or falling suddenly and irregularly, with consequent undesired fluctuations in the quantities and penetrating powers of the resulting X-rays. As to the first effect 40 above referred to, by employing a polyphase current supply, a given and very large amount of energy is converted into X-rays within the tube without however the occurrence of extreme maximum currents and potentials which, if occurring, would mechanically deteriorate the target by pitting or 45 digging the same by mechanical action. By use of a polyphase system however the relative fluctuations in the potential and cur-

rent impressed upon the X-ray tube are low, 55 that is, the maximum current or potential is relatively smaller, for a given area of energy diagram or is smaller for a given root-mean square energy or current value. In consequence the maximum current or potential, which determines the mechanical force of impact of the cathode particles, and therefore the matter of target destruction, are relatively low considering the energy delivered through the tube. And from this 60 reduction in maximum of potential and current, considering the energy passed through the tube, the penetration and quantity of the X-rays resulting are far more uniform than in the case where the potential and current fluctuate widely. As to the second 65 effect, when there is great fluctuation in the potential and current, the increased mechanical action upon the target due to the impact of the cathode particles causes liberation into the free gaseous space of the 70 X-ray tube of a large number of finely divided metallic particles from the material of the target at or near the focus spot. The result of the liberation of these metallic particles is irregularity in the vacuum 75 from moment to moment, due to the fluctuation in the rate of absorption of gas by this cloud of metallic particles, with the result that the vacuum in the X-ray tube becomes irregularly higher, causing the tube to emit X-rays of irregular quantity and penetration. Irregularity of vacuum results also because of liberation of gas, either 80 occluded or confined in small spaces or sacks 85 within the metal of the target, unto the free gas of the tube, and particularly that portion of the volume of the target which has been excavated by the impact of the cathode 90 particles. 95

Further variation in vacuum results from gas liberated from the target from that portion of the volume which is immediately adjacent to the crater excavated at the focus spot of the target. 100

By recourse to my improved excitation of an X-ray tube, where the differences between maxima and minima of potential and current are small, the liberation of the energy within the X-ray tube will not cause 105 the undesired effects above mentioned as would be the case where the expenditure of the same amount of energy in the X-ray

tube differences between maxima and minima of potential and current are great. In a practical sense, the result is, briefly, that with a given or ordinary X-ray tube, I can, 5 by my system, without destruction of or injury to the X-ray tube, or without impairing its efficiency or life, pass through it, in a given time, greater amounts of energy than has heretofore been possible or the 10 practice, with resultant production of X-rays at greater rate or activity.

For an illustration of one of the forms 15 my invention may take, reference is to be had to the accompanying drawings, in which:

Figure 1 is a diagrammatic view illustrating the apparatus and circuit arrangements 20 of my system. Fig. 2 is a vertical sectional view, partly in elevation, of a high potential three phase rectifying switch mounted in operative relation with a motor, inverted rotary or other suitable device, and a high potential three phase transformer. Fig. 3 25 is an end elevational view, partly in section, of the high potential three phase rectifying switch shown in Fig. 2. Fig. 4 is a view graphically representing the rectified current waves and their effect in the X-ray 30 tube.

Referring to Fig. 1, L and L¹ are the conductors of an electric supply circuit leading 35 to the motor side M of a motor generator or inverted rotary R, whose generator side G delivers three phase alternating current 40 to the three conductors 1, 2 and 3, a reversing or pole changing switch A being connected in the conductors 2 and 3 for reversing the direction of energy flow in the X-ray tube X if for any reason it be in the

wrong direction. In each of the conductors 1, 2 and 3 is inserted an adjustable non-inductive resistance 4 for maintaining the resistances of the 45 three transformer primary circuits equal. And the three movable contacts for adjusting the resistances 4 are preferably mechanically connected together, so as to insert or remove equal amounts of resistance in each 50 primary. The conductors 1, 2 and 3 lead to the primaries p¹, p² and p³, of the high potential step up transformer T, each being 55 adjustable as to its number of turns, the three movable contacts for this purpose being preferably mechanically connected together so that the number of turns in the 60 primaries is varied equally. These primaries are here shown connected in Y arrangement, though it is to be understood that the delta connection may be employed.

The high potential secondaries s¹, s² and s³ are here shown as Y connected, as the preferred connection, though the delta connection is within my invention. The three 65 phase transformer T having these three primary and secondary windings is of the

closed magnetic circuit type and has a minimum or practically no magnetic leakage for purposes hereinafter referred to. The neutral or common point of the three secondary windings, when Y connected, is connected 70 by conductor 5 to earth or ground at 6. And for this reason the Y connection is preferred.

From each secondary winding s¹, s² and s³ a connection is made through conductors h¹, h² and h³ to pairs of conducting arcs of 75 the rectifying switch E, a choke coil D intervening in such connection if desired, for the purpose of preventing any high frequency oscillations (the coils D being high frequency choke coils) from running back 80 to the transformer windings where they might cause insulation punctures or breakdowns.

From the opposed arcs of the rectifying switch E extend conductors i and i' leading 85 respectively to the cathode k and anode j of the X-ray tube X.

An ammeter F is connected in series with the tube X to measure the current consumed therein, such ammeter being, for example, 90 of the type described in Letters Patent of the United States No. 768,957, heretofore granted to me.

Referring to Fig. 2, a bench or base H, of wood or other suitable material, serves 95 to support the high potential rectifying switch E, the transformer T (contained in the metal transformer case I, containing oil) and the motor generator or inverted rotary R. As here represented, R is an inverted rotary receiving direct current and delivering three phase alternating current. A wooden spindle or shaft J has metal shaft terminals m, m having bearings n, n supported by the end walls o, o of the wooden 100 covering or casing which incloses the high potential polyphase rectifying switch E. One of the terminal shafts m is connected by an insulating coupling p with the shaft q of the inverted rotary R. Extending 105 through and carried by the spindle J are six metallic rods or wires r, s, t, u, v, and w, each incased in rubber or other insulating covering and support x. The wooden spindle J insulates each of these six rotating cross connectors or rods from every 110 other, and the insulating covering x, preferably of hard rubber, insulates each of the cross connectors to prevent premature or undesired sparking during operation. These 115 six cross connectors or metallic rods are divided into three pairs, the cross connectors of each pair being disposed at right angles with each other, but the cross connectors of the second pair progress at an angle of 60 120 mechanical degrees with respect to the cross connectors of the first pair, and the cross connectors of the third pair progress at an angle of 60 mechanical degrees with the cross connectors of the second pair or at an 125

angle of 60 mechanical degrees with the cross connectors of the first pair.

Coöperating with the cross connectors *r*, *s* respectively are the opposed pairs of conducting arcs 7, 8 and 9, 10, the arcs 7 and 9 being electrically connected together and with the conductor *h*² led up through the insulating tube 19 from the terminal of one of the high potential secondaries of the transformer *T*. Through a similar insulating tube 20 is led up a conductor *h*³ from the terminal of another high potential secondary which connects to the neighboring conducting arcs 11 and 13 opposed to the 15 conducting arcs 12 and 14, the cross connectors *t* and *u* coöperating with these opposed pairs of arcs. Similarly, through the insulating tube 21 extends a conductor *h*¹ communicating with the terminal of the third 20 high potential secondary winding of the transformer *T*, the conductor *h*¹ being connected to the arcs 15 and 17 which are opposed to the conducting arcs 16 and 18 respectively, the cross connectors *v* and *w* coöperating with these opposed pairs of arcs. The cross connectors do not touch the arcs in passing them, short air gaps intervening over which the current sparks. The 25 conducting arcs 8, 14, and 16 are electrically connected together and to the conductor *j*' and, as seen in Fig. 1, to the anode *j* of the X-ray tube *X*. And the arcs 10, 12, and 18 are connected together and to the conductor *i* which connects with the cathode *k* of the 30 tube *X*.

Between the neighboring pairs of the lower conducting arcs, as viewed in Fig. 2, which may be styled the supply arcs, since they are connected to the supply side of the 35 switch *E*, are disposed the insulating barriers 22 and 23, of mica, micanite, glass, or any suitable highly insulating material. And between the upper conducting arcs 8 and 10, which are on the distributing side 40 of the switch *E* and may, therefore, be styled distributing arcs, is disposed a similar insulating barrier 24; and between the distributing arcs 12 and 14 is a similar insulating barrier 25; and between the distributing 45 arcs 16 and 18 is a similar insulating barrier 26. These insulating barriers are supported, spaced and held in place by suitable means comprising vertically extending rods 27 and 28, preferably of insulating material.

The conducting arcs 7 and 18 inclusive, are supported upon the tubes 29, 30, 31, 32, 33, and 34, of porcelain, or other insulating material, disposed upon the parallel rods 50 35. And these cross connectors and their coverings and the wooden spindle *J* are all mechanically balanced so that the center of gravity of the moving system is in the axis of the rotating spindle *J*. The spindle *J* being preferably mechanically connected to

the rotating member which generates the three phase alternating current, insures that the rotating cross connectors are in exact synchronism with the alternating current delivered from the alternating current side 55 of the inverted rotary *R*. Or, if the alternating current generator be driven by other means, the spindle *J* is nevertheless preferably mechanically connected to the rotating element of the alternating current generator. 75

The conducting arcs, as here shown, for a three phase system, have an angular extent of something preferably slightly less than 60 mechanical degrees, 60 mechanical 80 degrees in the switch *E* corresponding with 120 electrical degrees. It follows, therefore, that since the cross connectors of the different pairs are 60 degrees in advance or in arrears of each other, it means that 85 these cross connectors are disposed at an angle of 120 electrical degrees with respect to each other, the same being the interval in electrical degrees between the different phases of a symmetrical three phase current. 90

The operation is as follows: The operator brings the motor *M* of the inverted rotary into communication with a source of current and brings the inverted rotary or the alternating current generator up to speed, thus 95 generating three phase current of desired frequency and rotating the cross connectors of the rectifying switch *E* in synchronism with that current. The transformer *T* then delivers high-potential three phase current 100 which is rectified by the switch *E* and supplied to the tube *X*. Thus, assuming the cross connectors *r*, *s*, *t*, *u*, *v* and *w* to be rotating in a clockwise direction, as viewed in Figs. 1 and 3, the cross connector *w* is just 105 beginning to admit current from secondary *s*¹ through arcs 17 and 18 to the one terminal *k* of the X-ray tube *X*. Its companion cross connector *v* is out of circuit as is also the cross connector *u* associated with the secondary *s*². Cross connector *t* is just leaving arcs 11 and 12, having heretofore admitted current from the secondary *s*² to the terminal *k* of the tube. Cross connector *s* is out of circuit but its associate *r* is admitting current from secondary *s*¹ through arcs 7 and 8 to the other terminal *j* of the X-ray tube. As 110 these cross connectors continue to rotate they keep passing both the positive and negative current waves of each phase through the tube *X* all in the same direction; and more than this, they correlate and superimpose the different half waves of the phases so that for certain periods of time a plurality of 115 phases coöperates with each other in impressing energy upon the tube *X* all in the same direction, whereby the tube is always traversed by energy, and the minimum potential to which the tube is subjected is 120 greater than the maximum potential deliv- 125 130

ered by any one of the secondaries alone. The energy is all passed through the tube X in the same direction, the energy of each half wave of each phase being passed through the tube and all in the same direction exciting the tube to great intensity and keeping the excitation always at a high intensity, there being no time when there is no energy passing through the tube. And the minimum energy at any instant is sufficient to fully excite the tube.

As seen from Fig. 4, the switch E rectifies the current in each phase, so that we have the overlapping half waves $a, b, c, a', b',$ and c' , a, b and c representing the three different phases.

a, b' and c' indicate the rectified or turned over negative (for example) half waves. And the length of the conducting arcs of the switch E being substantially 120 electrical degrees, and the angular relation of the cross connectors with respect to the windings on the rotating member of the alternating current generator is so chosen and fixed, that each cross connector is active or in circuit for a time corresponding with the distance d . There results then in the circuit of the tube X a fluctuating current of frequency triple the frequency of a half cycle of one phase supplied by the transformer T, this triple frequency current being represented by the curve e in the upper part of Fig. 4. This curve is obtained by adding the ordinates of the curves below during such periods as the different phases are actively in circuit as controlled by the switch E. It will be noted, therefore, that the minimum potential upon the terminals of the tube X, represented by the distance f , is greater than the potential of any one of the secondaries of the transformer T. This potential f is dependent upon the maximum potential of a phase multiplied by twice the sine of half the angle between the phases. This curve shows that the tube X is constantly subjected to a potential whose minimum is f and which is always greater than the potential delivered by one phase of the transformer T, and this minimum potential f is sufficient to excite the tube X to very high intensity. This potential varies as shown by the upper curve e so that the energy through the tube X fluctuates, but at no time has it a potential less than the potential f .

By having practically no inductance in the circuits of the primaries of the transformer T, other than their own inductances, and by making the transformer T of a minimum or practically no magnetic leakage, and by mechanically connecting the shaft J to the rotating element of the device generating the alternating current, I secure a maximum efficiency of conversion, along with an excitation of the tube X to an intensity which has never heretofore been at-

tained, the features enumerated contributing to this result, and especially to the result of preventing inverse discharge in the tube X, inverse discharge being energy flowing in the wrong direction through the tube X.

The transformer T may have very low magnetic leakage, as above stated, so that in operation the spark drawn between a cross connector and its arcs will not be long drawn out after the cross connector has left the trailing tips of the arcs. However, where this drawing-out of the sparks is to be allowed, a transformer of greater magnetic leakage may be employed.

The conducting arcs of the switch E are made somewhat less than 120 electrical degrees in extent to take care of the case where the currents in the three phases do not maintain an interval of 120 electrical degrees between each other, and to take care of any other departures from the ideal conditions.

While I have here illustrated my invention as involving a three phase current, it is to be understood that my invention refers to polyphase currents in general, such as quarter phase or two phase currents or currents of other phase relations and numbers. And while I have shown the conducting arcs of the switch E in alinement, it is to be understood that they may be disposed out of alinement and the cross connectors then suitably changed in their relations to the arcs. It is to be understood also that the arcs may be otherwise disposed, in which case a greater number of insulating barriers may be required. In the arrangement illustrated a minimum of five insulating barriers is required, and this with the alinement of the conducting arc makes the size of the rectifying switch a minimum for any given potential.

What I claim is:

1. In an X-ray system, the combination with a source of polyphase alternating current, of a step-up transformer supplied by said source, a high potential polyphase rectifying switch driven in synchronism with said current deriving energy from said transformer, and an X-ray tube continuously traversed by the uninterrupted unidirectional current derived from said switch.

2. In an X-ray system, the combination with a source of polyphase current, of a step up transformer, an X-ray tube, and a high potential polyphase rectifying switch intervening between said transformer and said tube, said switch causing overlapping unidirectional current waves to be impressed upon said tube, whereby said tube is continuously subjected to a potential higher than the potential of any phase supplied to said rectifying switch.

3. A system for producing X-rays of high intensity and greater uniformity in charac-

- teristics comprising the combination with an X-ray tube, of means for producing high potential uni-directional overlapping current impulses, and a circuit including said means and said X-ray tube.
4. In an X-ray system, the combination with a source of polyphase current, of a polyphase transformer, an X-ray tube, and a high potential polyphase rectifying switch intervening between said transformer and said tube, said switch comprising conducting arcs and cross connectors, the period of cooperation between a cross connector and an arc being substantially equal to the time of non-overlapping of a wave of one phase with respect to a wave derived from another phase.
5. In an X-ray system, the combination with a generator of polyphase current, of a polyphase transformer, an X-ray tube, and a high potential polyphase rectifying switch intervening between said transformer and said tube, said switch comprising relatively rotatable arcs and cross connectors, the movable element of said switch being mechanically connected to the movable element of said generator.
6. In an X-ray system, the combination with a source of polyphase current, of a polyphase transformer, an X-ray tube, and a polyphase rectifying switch intervening between said transformer and said tube, said switch being driven in synchronism with the polyphase current, and said transformer having practically no magnetic leakage whereby short circuiting between different phases is prevented.
7. In an X-ray system, the combination with a source of polyphase current, of a polyphase transformer, an X-ray tube, and a polyphase rectifying switch intervening between said transformer and said tube, said switch comprising conducting arcs and cooperating cross connectors so disposed that energy is continuously passed through said tube.
8. The combination with a source of polyphase current, of a polyphase transformer, an X-ray tube, and a polyphase rectifying switch intervening between said transformer and said tube, said switch comprising conducting arcs and cooperating cross connectors so disposed that energy is continuously passed through said tube, the minimum potential to which said tube is subjected being greater than the potential of any phase.
9. In an X-ray system, the combination with a source of polyphase current, of a polyphase transformer, an X-ray tube, and a polyphase rectifying switch intervening between said transformer and said tube, said tube being continuously subjected to a potential whose minimum is dependent upon a potential which is twice the sine of half the angle of phase difference between the respective phases multiplied by the maximum potential of a phase.
10. In an X-ray system, the combination with a source of polyphase alternating current, of a polyphase step-up transformer having low magnetic leakage, an X-ray tube, and a high potential polyphase rectifying switch intervening between said transformer and said X-ray tube.
11. In an X-ray system, the combination with a machine delivering polyphase alternating current, of a step-up polyphase transformer, an X-ray tube, a high potential polyphase rectifying switch intervening between said transformer and said X-ray tube, and a mechanical connection between the rotating elements of said machine and said polyphase rectifying switch.
12. In an X-ray system, the combination with a machine delivering polyphase alternating current, of a step-up polyphase transformer having low magnetic leakage, an X-ray tube, a high potential polyphase rectifying switch intervening between said transformer and said X-ray tube, and a mechanical connection between the rotating elements of said machine and said polyphase rectifying switch.
13. In an X-ray system, the combination with a source of polyphase alternating current, of a step-up polyphase transformer, a high potential polyphase rectifying switch comprising pairs of opposing supply and conducting arcs, a cross-connector associated with each pair, a pair of supply arcs connected together and to each transformer secondary, an X-ray tube, one terminal of said X-ray tube connected to half of the distributing arcs, and the other terminal of said X-ray tube connected to the remainder of said distributing arcs.
14. In an X-ray system, the combination with a source of polyphase alternating current, of a constant potential step-up transformer, a high potential polyphase rectifying switch comprising a plurality of pairs of supply and distributing arcs, a cross-connector for each pair of arcs, the supply arcs associated with the transformer secondaries, an X-ray tube, half of the distributing arcs connected with each other and with one terminal of said X-ray tube, and the remainder of said distributing arcs connected with each other and to the other terminal of said X-ray tube.
15. In an X-ray system, the combination with a source of polyphase alternating current, of a high tension step-up transformer, an X-ray tube, and a synchronously driven high potential polyphase rectifying switch comprising conducting arcs and associated cross connectors, a pair of supply arcs for each phase, a pair of distributing arcs for each phase, the arcs and their cross connectors being so disposed that energy from

both the positive and negative half waves of all the phases is passed through said tube all in the same direction.

16. In an X-ray system, the combination with a source of polyphase alternating current, of a high tension step-up transformer, an X-ray tube, and a synchronously driven high potential polyphase rectifying switch comprising conducting arcs and associated cross connectors, a pair of supply arcs for each phase, a pair of distributing arcs for each phase, the arcs and their cross connectors being so disposed that energy from both the positive and negative half waves of all the phases is passed through said tube all in the same direction, a pair of arcs and its cross connectors being in circuit for a period corresponding with the phase difference between the phases of said source of alternating current.

17. In an X-ray system, the combination with a source of polyphase alternating current, of a high tension step-up transformer, an X-ray tube, and a synchronously driven high potential polyphase rectifying switch comprising conducting arcs and associated cross connectors, a pair of supply arcs for each phase, a pair of distributing arcs for each phase, the arcs and their cross connectors being so disposed that energy from both the positive and negative half waves of all the phases is passed through said tube all in the same direction, and said tube continuously subjected to a potential at least as great as the maximum potential of one of the phases.

18. In an X-ray system, the combination with a source of polyphase alternating current, of a high tension step-up transformer, an X-ray tube, and a synchronously driven high potential polyphase rectifying switch comprising conducting arcs and associated cross connectors, a pair of supply arcs for each phase, a pair of distributing arcs for each phase, the arcs and their cross connectors being so disposed that energy from both the positive and negative half waves of all the phases is passed through said tube all in the same direction, and said tube continuously subjected to a potential whose minimum exceeds the maximum potential of any phase.

19. In an X-ray system, the combination with a source of polyphase alternating current, of a step-up polyphase transformer, an X-ray tube, and a polyphase rectifying switch intervening between said transformer and said X-ray tube and comprising a pair of supply and distributing arcs and cross connectors for each phase, the supply arcs for each phase being connected together, and the distributing arcs for each phase being connected respectively to different terminals of said X-ray tube.

20. In an X-ray system, a source of three-

phase alternating current, a three-phase step-up transformer having its secondaries connected in Y relation, an X-ray tube, and a three-phase rectifying switch intervening between said transformer secondaries and said X-ray tube comprising a pair of supply and distributing arcs and cross connectors for each transformer secondary, the supply arcs for each secondary being connected together and to that secondary, and the distributing arcs of each pair being connected respectively to the different terminals of said X-ray tube.

21. In an X-ray system, the combination with a three-phase alternating current generator, of a three-phase step-up transformer, an X-ray tube, and a three-phase rectifying switch intervening between said transformer and said X-ray tube and comprising a pair of supply arcs and a pair of distributing arcs and cross connectors for each phase, the supply arcs for each phase being connected together, the distributing arcs for each phase being connected respectively to the different terminals of said X-ray tube, and said cross connectors mechanically connected to the rotating element of said generator.

22. In an X-ray system, the combination with a three-phase alternating current generator, of a three-phase step-up transformer, an X-ray tube, and a three-phase rectifying switch intervening between said transformer and said X-ray tube and comprising a pair of supply arcs and a pair of distributing arcs and cross connectors for each phase, the supply arcs for each phase being connected together, the distributing arcs for each phase being connected respectively to the different terminals of said X-ray tube, and said cross connectors mechanically connected to the rotating element of said generator, all of said supply arcs being disposed in alignment with each other and all the distributing arcs disposed in alignment with each other, said cross connectors for each phase being disposed at right angles to each other, and the cross connectors for the several phases progressing with respect to each other by an angle corresponding with the angle between the current phases.

23. A system of X-ray tube excitation comprising the combination with an X-ray tube, of means delivering high potential polyphase current, and means delivering to said tube uni-directional energy of said polyphase current.

24. A system of X-ray tube excitation comprising the combination with an X-ray tube, of a source of polyphase current, a step-up polyphase transformer deriving energy from said source, a synchronous high potential rectifying switch intervening between said transformer and said X-ray tube, whereby uninterrupted uni-directional en-

ergy is passed through said tube and fluctuations in vacuum and deterioration of the anti-cathode of said X-ray tube are lessened.

25. A system of X-ray tube excitation comprising the combination with an X-ray tube, of a source of polyphase current, a step-up polyphase transformer deriving energy from said source, a synchronous high potential rectifying switch intervening between said transformer and said X-ray tube, whereby uninterrupted uni-directional energy is passed through said tube and fluctuation in vacuum and deterioration of the anti-cathode of said X-ray tube are lessened, said transformer having low magnetic leakage whereby short circuiting between different phases is prevented.

26. In a system of X-ray tube excitation, the combination with an X-ray tube, of a source of polyphase current, a step-up polyphase transformer, a high potential polyphase rectifying switch intervening between said transformer and said X-ray tube and comprising pairs of opposed conducting arcs and coöperating cross connectors, a pair of supply arcs for each phase, a pair of distributing arcs for each phase, the length of each arc in electrical degrees corresponding substantially with the interval between the phases of said source of current, means for driving the rotary element of said rectifying switch in synchronism with the current, said transformer having low magnetic leakage, whereby short circuiting in said rectifying switch is prevented.

27. A system of X-ray tube excitation

comprising the combination with an X-ray tube, of a source of high potential polyphase alternating current, and means for directing through said tube uni-directional uninterrupted energy from both the positive and negative waves of said polyphase current.

28. A system of X-ray tube excitation comprising the combination with an X-ray tube, of a source of high potential polyphase alternating current, and synchronous switching means for directing through said tube uni-directional uninterrupted energy from both the positive and negative waves of said polyphase current.

29. A system of X-ray tube excitation comprising the combination with an X-ray tube, of means delivering high potential polyphase current, and synchronous switching means delivering to said tube uni-directional energy of said polyphase current.

30. A system of X-ray tube excitation comprising the combination with an X-ray tube, of a plurality of high potential transformer secondaries having a common grounded terminal, and synchronous switching means interposed between the remaining terminals of said secondaries and said X-ray tube for delivering to said tube uni-directional energy.

In testimony whereof I have hereunto affixed my signature in the presence of the two subscribing witnesses.

HOMER CLYDE SNOOK.

A. E. STEINBOCK,

DANIEL WEBSTER, Jr.

It is hereby certified that in Letters Patent No. 1,131,870, granted March 16, 1915, upon the application of Homer Clyde Snook, of Philadelphia, Pennsylvania, for an improvement in "Polyphase X-Ray Systems," errors appear in the printed specification requiring correction as follows: Page 4, line 105, for the word "arc" read *arcs*; page 5, line 109, claim 14, strike out the words "constant potential;" and that the said Letters Patent should be read with these corrections therein that the same may conform to the record of the case in the Patent Office.

Signed and sealed this 21st day of September, A. D., 1915.

[SEAL.]

J. T. NEWTON,
Acting Commissioner of Patents.
